UNITED STATES PATENT OFFICE

SAMUEL E. HITT, OF ELYRIA, OHIO

PROPELLER TURRET FOR PROPULSION AND STEERING OF AEROSHIPS

Application filed August 12, 1929. Serial No. 385,238.

This invention relates to means for the propulsion and steering of aeroships, whether on the water or in the air and is particularly adapted to the aeroship, described and shown in my application filed March 26th, 1928, for Air and water craft, Serial No. 264,634.

In general, my invention consists of a propeller driven by a combustion engine and mounted on a turret having a compartment for operators and capable of being turned in any direction by electric power under centralized control, so that the engine operators can start and stop the propeller or run the same at any speed desired and the pilot can 15 turn the turrets in groups to steer and propel the aeroship.

As now planned, my aeroship has thirty-two turrets for propulsion and steering, each equipped with a six hundred and twenty-five 20 (625) horse power engine making a total of twenty thousand (20,000) horse power.

My reason for providing the propulsion units with combustion engines is to distribute the weight over the hull units and avoid the 25 heavy load of a large generator unit in the power house as is required in the electric propeller drives described in my application, Propulsion and steering of aeroships, Serial No. 349,916, filed March 26th, 1929.

The objects of the invention are as follows:—

To provide combustion engine drives for the air propeller units for the propulsion and 35 steering of the aeroship.

To provide turntable mounting for the said propulsion unit.

To provide a turret for the said propulsion unit, with room for one or more operators.

To provide the turret with a fuel supply tank.

To provide means for filling the fuel supply tank.

To provide the turret with an oil tank.

To provide the turret with a water tank for water cooling of the engine cylinders.

To provide means for filling the water tank.

To provide means for turning the propulsion units so that all of the propellers can be turned to head into the wind or toward the head resistance or at such angle between the two, i. e., the angle of resultant resistance, according to the relative velocity of the aeroship and wind, as will perfectly equalize those forces and cause the aeroship to maintain a course straight ahead without drift as described and shown in my application, Propulsion and steering of aeroships, Serial No. 349,916, filed March 26th, 1929.

To provide the turret with an annular gear and mechanism so that the turning motion of the turret is under centralized control.

To provide the turret turntable mounting with a king post to carry the propeller pull and relieve the rollers from end thrust.

To provide a hollow king post for fuel piping.

To provide the fuel supply pipe with a valve inside the turret and accessible to the operator.

To provide the fuel pipe with an automatic valve for minimum and maximum height of fluid.

To provide a propulsion unit with an engine shaft extension between the propeller and engine of sufficient length to allow a long nose construction of turret to ease the slip stream from the propeller.

To provide the engine shaft and extension with a flexible coupling.

To provide the engine shaft and extension with frictionless bearings throughout to secure maximum power for minimum weight.

To provide the propulsion unit with air tight compartment for operators with means for ventilating the same.

To provide the propulsion unit with practically a sound proof compartment, that op-

- erators may not become fatigued by long hours of service.
- To provide the propulsion unit with a compartment large enough for a bunk or hammock so that one operator may be resting while another is on duty.
- To provide the turret with a partition between the engine room and operator's compartment to deaden the hum and vibration of the engine.
- To provide the turret with a telephone connected to the pilot house.
- To provide the turret with signal lights and electric gongs connected to the pilot house.
- To provide a turret with a relatively small cross section to reduce the air head resistance to a minimum.
- To provide a turret with head room so that the engine operators can stand and walk erect.
- To provide the propulsion unit with a combustion engine entirely enclosed within the turret.
- To provide the propulsion unit with an engine of narrow width to allow passageway on each side of the engine.
- To provide the propulsion unit with an engine adapted to the turret so that all parts of the drive are accessible to inspection and repair under running conditions.
- To provide the propulsion unit with a combustion engine with moving parts enclosed to effect noiseless operation.
- To provide the engine compartment with a telpher or small crane with hand hoist so that a cylinder can be removed at sea.
- To provide the propulsion unit with a water cooled engine.
- To provide a radiator for the water cooling system.
- To provide the radiator with cooling vanes projecting out from the general contour of the turret.
- To provide radiator vanes that follow the stream lines from the air propellers so that such vanes will offer a minimum head resistance.
- To provide the propulsion unit with a starting device.
- To provide the propulsion unit with all necessary equipment for starting and stopping the engine so that the propeller drive is under complete control of the operator.
- To provide the propulsion unit with means for stopping the engine from the pilot house in case the operators become disqualified and do not respond to a stop order.
- With the above and other objects in view, the invention further includes the following novel features and details of construction, to be hereinafter more fully described, illustrated in the accompanying drawings and pointed out in the appended claims.

In the drawings:—

Fig. 1 is an end view of one of the hull units.

Fig. 2 is a sectional plan of the turret.

Fig. 3 is an elevation of the turret, partly in section on line 3—3 of Fig. 2.

Fig. 4 is a sectional elevation on line 4—4 of Fig. 2.

Fig. 5 is an enlarged detail of the roller spider.

Fig. 6 is a half sectional elevation and half side view of the spider.

Fig. 7 is a section on the line 7—7 of Fig. 3.

Fig. 8 is a section of one radiator sector and fastenings.

Fig. 9 is a plan of the turning drive for one turret.

Fig. 10 is a plan of all the turrets, turning mechanism and turning motors for the two hulls of my aeropship.

Fig. 11 is an electrical diagram showing centralized control for turning the turrets for the two hulls of my aeropship.

Referring to the drawings in detail, where-

in like characters of reference denote corresponding parts, in Fig. 1, is the hull, 2 the main frame and 3 intermediate framing between the hull 1 and the main frame 2. When the aeropship rides upon the water the hull supports the load above it. When the aeropship rises and the hull clears the water, the framing 2 and 3 carry the hull. 4 is one of the masts secured to the hull 1 and framing 2—3. 5 is one of the wings pivotedly mounted on the mast 4. 6 is one of the turrets mounted on the port deck 7 of the main frame 2. 8 is one of the turrets mounted on the starboard deck 9 of main frame 2. 10 are the air propellers of the turret units. 11—11 are the cabins carried by the main frame 2.

In Fig. 2, the air propeller 10 is shown carried by a turret 20 formed on slip stream lines to reduce the head air resistance and the drag to a minimum. The air propeller 10 is driven by a combustion engine 21. In plan the engine compartment 22 has parallel sides 22', the forward compartment 23 is of projectile form and tapers from the engine compartment to the propeller, while the sides 19' of the rear compartment 19 for the operators taper off as the stern of a ship.

In Fig. 3, the air propeller 10 is shown driven by the combustion engine 21, by the shaft 24 and flexible coupling 25 mounted in bearings 26 and 27. The engine is started by a six cylinder combustion engine 28 through the clutch 29 and gears 30 and 31. One of the operators is shown telephoning to the pilot house with phone 32. 33 is a bunk which can be folded against the side of the compartment when not in use. 34 is the radiator for the water cooling system of the engines 21 and 28. Radiator vanes 35 project outside the shell 36 and are shown to follow the slip stream lines from the propeller.

ler 10. The upper portion of the turret as described embodying the propeller, engine and operators' compartments, is mounted on a cylindrical portion 37 supported by the deck 7. The oil tank 38 and the water tank 39 are placed under the floor of the operator's compartment.

The lower portion 37 of the turret is shown in more detail in Fig. 4 in which the engine 21 is shown with vertical cylinders, having 10 passageways between the engine and sides 22, to make the engine compartment narrow, now planned 8 feet wide. The engine 21 is mounted on a revolvable base 40 having vertical webs 41 and bottom plate 42. The fuel tank 43 is made in sections which set on the bottom plate 42 between the webs 41. The base 40 has a track 44 resting on conical rollers 45 which run on the track 46 of the stationary base 47 secured to the upper deck 7 or 9 of the aeropship. The revolvable base 40 is pivoted in the center, having a hub 48 which turns on the king post 49 of the stationary base 47. The revolvable base 40 carries an outer track 50 engaged by rollers 51 carried by brackets 52 integral with or secured to the stationary base 47 to prevent tilting reaction of the propeller from causing a binding or breaking action on the king post. The revolvable base 40 carries an annular gear 55 engaged by the pinion 56 on the shaft 57 mounted on the bracket 58 and driven by the electric motor 59 through worm 60 and worm gear 61. The annular gear 55 is covered by a shield 62 fastened to the casing 37 of the revolvable base.

The fuel supply line 130 connects with the feed pressure line 131 through the check valve 132, the vertical riser 133 passing up through the hollow king post 49 above the engine room floor 134 and carries valves 135 and 136 serving the filling pipes 137 and 138, which are stationary and held by the clamp 139 and pass downwardly into the fuel tank 43, passing 45 through a cylindrical head 140 with inner stuffing box 141 and outer stuffing box 142 which seal the fuel tank 43.

Fig. 5 shows a plan of the roller spider in which the rollers 45 are held equally distant 50 from the center of the turret by radial arms 70 secured to the hub 54 which is free to turn on the king post 49. The rollers 45 are kept equally distant by the cage 71.

Fig. 6, the rollers 45 turn on the spindles 72 of the radial arms 70 and are held endwise by collars 73, washers 74 and nuts 75. The stud shafts 76 of the arms 70 project out beyond the nuts 75 and rollers 45, the cage 71 being grooved at 77 to drop down over the stud shafts 76, the cage 71 being easily removable. The radial arms 70 screw into the hub 54 as at 78, and are further held by lock nuts 79, so that adjustments can be made until all the 60 rollers make contact on both the upper track

44 and the lower track 46 and until the turret turns true about the king post 49.

In Figs. 7 and 8, 80 are longitudinal members of the framing of the forward compartments, 81 are sectors of the radiator for the 70 water cooling system for the combustion engines. Sectors 81 are removable from the outside and are held in place by clips 82 and bolts 83. Radiator sectors 81 are piped from the inside with bypass valves so that should one 75 of the sectors start to leak that sector can be cut out.

In Fig. 9, 50 is the outside track, 51 are the rollers for holding the turret down, 55 is the annular gear, 56 the pinion, 59 the turning 80 motor, 60 the worm and 61 the worm gear.

The general scheme for the propulsion and steering of the aeropship is shown in Fig. 10, in which 90 and 91 are the two forward turrets and 92 and 93 are the two aft turrets on 85 port hull 1, used for both propulsion and steering of the aeropship. Turrets 90 and 91 are turned by the electric motor 94 through cross shaft 95 and gearing 60, 61, 56 and 55 as shown in more detail in Figs. 3, 4 and 9. Aft turrets 92 and 93 are turned by the electric motor 96 through cross shaft 97 and gearing 60, 61, 56 and 55 as shown in Figs. 3, 4 and 9. Intermediate turrets 100 and 101 are turned by the electric motor 102, cross shaft 103, miter gears 104 and 105, longitudinal shafting 106 and 107, and gearing 60, 61, 56 and 55, as shown in Figs. 3, 4 and 9. The intermediate units 100 and 101 are generally used for the propulsion only. To steer the 100 aeropship to port the turrets 90 and 91 are turned to port and the aft turrets 92 and 93 are turned to starboard, in like manner, to steer the aeropship to starboard, the forward turrets 90 and 91 are turned to starboard and the aft turrets 92 and 93 are turned to port. To steer the aeropship sideways or at an oblique angle, all of the turrets 90, 91, 92, 93, 100 and 101 are turned in the direction desired. 110

The above description is applicable also to the propulsion and steering units on starboard hull 2 where like parts are given the same numbers primed.

Fig. 11 is a wiring diagram for the turret turning motors in which 94 and 94' are the forward motors, 102 and 102' are the intermediate motors and 96 and 96' are the aft motors. These motors are all wired to the pilot house where controller 110 has circuit leads 111 and 112 to the motor 94, controller 115 has circuit leads 116 and 117 to the motor 102 and controller 120 has leads 121 and 122 to the motor 96. The controllers 110, 115 and 120 are reversing and the motors are all equipped with electric brakes so that when any group of turrets has reached the desired direction, the controller is turned to the "off" position as at 125, for instance, and that motor stops. 120 130

The circuits for hull 2 are similar with same numbers primed for like parts.

The operation of my invention is as follows:—

- 5 The turret operators are given general instructions when they enter the turrets. When the time of departure draws near, the pilot signals by electric gong in each turret, meaning "Are you ready". Each operator answers "Ready". When all the turret numbers on the pilot's signal board show clear, the pilot signals "Start". All the turret operators receiving the signal, start their engines on slow speed for 1 gong signal. When under way, the engines are speeded up as the signals come in 2, 3 or 4 gongs for instance.
- 10 The pilot gives personal direction to the switchboard operator relative to the angle to which the forward, intermediate and aft groups of turrets are to make with the axis of the aeroplane. The pilot watches his compass and gradually brings the aeroplane to the course desired, when all of the turrets are turned to the angle required to hold the course.
- 15 The pilot then signals for increased speed. The speed is gradually increased until the hulls are skipping on top of the waves, when the turret operators are signaled to hold the speed.
- 20 On coming into port the procedure is reversed, the turret operators are signalled to reduce speed several times when slowing down from a speed of 100 to 140 miles or more per hour. When the engines stop, the order is given to cast anchor. The passengers are taken off by a local boat.
- 25 When conditions are good and the pilot wishes to make the best time, the propeller speeds are increased until the hulls clear the water, the hulls rising about ten feet above the crests of the highest waves.

What I claim is:—

1. In an aeroplane or similar craft having a plurality of propulsion units, the said propulsion unit consisting of an air propeller and combustion engine drive, turret mounting for each of the said propulsion units, and electric motors, shafting and gearing for turning the forward, intermediate and rear turrets in groups or all together, substantially as specified.
- 45 2. In an aeroplane or similar craft having a plurality of propulsion units, the said propulsion unit consisting of an air propeller and a combustion engine drive, turret mountings for the said propulsion units, electric motors and gearing for turning the said turrets in any desired direction, and electric controllers for each of the said electric motors, to turn the said turrets in forward, intermediate or rear groups, separately or all together to steer and propel the said aeroplane, substantially as specified.
- 50 3. In an aeroplane or similar craft, a stationary base member including a king post and an

annular bearing concentric with the king post, a turret base having a downward projection journaled upon the king post and having an annular bearing portion facing the said bearing, a plurality of outer rollers disposed between the said bearing and bearing portion and having their axes radial of the king post, the turret base having an external gear formed thereon, a pinion journaled upon the base member on a vertical axis and meshing with the said gear, and means for rotating the pinion so as to revolve the turret.

70 4. In an aeroplane or similar craft, an assemblage as per claim 3, in which the said bearing and bearing member present opposed conical faces diverging from a common point on the axis of the turret, and in which the said rollers are conical and taper toward the said point.

75 5. In an aeroplane or similar craft, a hull, two parallel rows of stationary turntables extending longitudinally of the craft at opposite sides of and equidistant from the vertical and longitudinal medial plane of the hull, a turret rotatably mounted on each turntable; two mechanisms respectively connecting the turrets at each side of the said plane, each mechanism including a shaft extending longitudinally of the craft and gearing interposed between each shaft and the adjacent turrets; and control mechanism for simultaneously rotating the two shafts so as to turn the turrets at opposite sides of the said plane respectively in the same rotational directions.

80 6. In an aeroplane or similar craft, a hollow king post, a turret rotatable thereon, an annular fuel tank in lower portion of the turret, an internal combustion engine supported within the turret above the fuel tank; and a fuel supply duct extending upwardly through the bore of the king post and the bore of the fuel tank, the said duct being recurved within the turret and extending downwardly into the fuel tank.

85 7. In an aeroplane or similar craft, a turret mounting and propulsion unit assembly as per claim 6, including a floor supported within the turret above the fuel tank and below the engine, the floor having a central aperture, and the recurved portion of the fuel duct extending downward into the tank through the said aperture.

90 8. In an aeroplane or similar craft, a turret mounting and propulsion unit assembly as per claim 6, including a floor supported within the turret above the fuel tank and below the engine, the floor having a central aperture, and the recurved portion of the fuel duct extending downward into the tank through the said aperture, and a valve disposed above the said floor for controlling the connection between the recurved portion of the fuel duct and the portion of the said duct which extends upwardly through the bore of the tank.

9. In an aeroship or similar craft, a propulsion unit consisting of an air propeller and combustion engine drive, a turret mounting for the propulsion unit, the said turret
5 provided with an annular outer track, guide rollers engaging the said track, and stationary elements in which the said rollers are mounted, the stationary elements being arranged to take the thrust due to the tilting
10 action of the said propeller, substantially as specified.

In testimony thereof, I affix my signature.
